UNITED STATES PATENT OFFICE.

VICTOR ROSENHAGEN, OF BELLEVUE, KENTUCKY, ASSIGNOR TO THE HYDRO HIGH VACUUM PUMP COMPANY, OF BELLEVUE, KENTUCKY, A CORPORATION OF KENTUCKY.

VACUUM PUMP.

Application filed July 8, 1922. Serial No. 573,567.

To all whom it may concern:

Be it known that I, VICTOR ROSENHAGEN, a citizen of the United States of America, and a resident of Bellevue, in the county of 5 Campbell and State of Kentucky, have invented a new and useful Improvement in a Vacuum Pump, of which the following is a specification.

My invention relates to pumps generally 10 referred to as vacuum pumps, and to a system in which same are employed.

An object of my invention is to provide an efficient pump of this type.

Another object of my invention is to provide 15 a pump which will produce a perfect vacuum.

Another object of my invention is to provide a simple device for the purposes stated.

These and other objects are obtained by 20 means described herein, and disclosed in the accompanying drawing, in which:

Fig. 1 is an elevation showing a pump and associated mechanism embodying my invention embraced in a heating system.

Fig. 2 is a fragmental sectional view of a 25 fluid supply tank and valve forming details of my invention.

Fig. 3 is a side elevation of a pump embodying my invention.

Fig. 4 is a plan view of the device shown 30 in Fig. 3.

Fig. 5 is an enlarged sectional view on line 5-5 of Fig. 3.

Fig. 6 is a sectional view on line 6-6 of 35 Fig. 5.

Fig. 7 is a sectional view on line 7-7 of Fig. 6.

Fig. 8 is a fragmental sectional view on 40 line 8-8 of Fig. 4.

Fig. 9 is a sectional view on line 9-9 of Fig. 2.

Fig. 10 is an enlarged, sectional view on 45 line 10-10 of Fig. 8.

Fig. 11 is an enlarged sectional view on line 11-11 of Fig. 4.

Fig. 12 is a plan view taken on line 12-12 of Fig. 11.

Fig. 13 is a perspective view showing the under face of a valve shown in Fig. 11, 50 forming a detail of my invention.

Fig. 14 is a perspective view showing the upper face of the valve shown in Fig. 13.

Generally my invention comprises a shaft 55 8 which may be driven from any suitable source, one end of which extends into a

housing 14 and carries a rotor 9 to which a fluid such as water may be fed, the rotor serving to throw the fluid outwardly, thereby creating a precipitous flow of fluid, which flow of fluid is employed to create a 60 vacuum in a given system, the system being provided with automatic means for controlling the motor and the conditions within the system.

A suitable support 10 has suitable bearings 11 and 12 for the shaft 8, one end of 65 which shaft is operatively connected with a motor 13 and the other end of which shaft extends into a housing 14. The housing remains stationary and has formed within it 70 a chamber 15 within which the rotor 9 is disposed. In Fig. 5 the rotor and shaft 8 are shown as being formed integral with one another, although this integral structure is not indispensable. Suitable roller bearings 75

16 are employed between the shaft 8 and the bearings 11 and 12. As shown in Fig. 5 a sleeve 17 is interposed between the journal box 11 and the bearings 16, and has mounted on it the casing 14. The sleeve also 80 carries a suitable stuffing box arrangement 18. The housing 14 is in two sections which may be secured upon one another by any suitable means such as bolts 19. The forward section 20 of the housing is mounted 85 upon the sleeve 17. The rear section 21 of the housing has a central aperture 22 concentric with the shaft 8 and a valve block 23 extends thru the aperture 22. The valve block, is secured, upon the annular flange 90 24 formed on the rear section 21, by suitable bolts 25. The forward end 26 of the valve block extends into a recess 27 formed centrally within the rotor 9. A pair of ways or ducts 270 and 28 is formed in the valve block, the duct 28 registering at its rear end with the bore of a pipe 30. At their forward ends the ducts are enlarged and are spaced from one another by a diametrically extending web 31 formed on the valve block. The 95 rotor 9 comprises a disc-like element, centrally within which are formed spiral ducts 32 which extend from the periphery of the rotor to the recess 27 formed centrally of the rotor. The ducts 32 are adapted to communicate with the enlarged ends of the ducts 270 and 28. The side faces of the rotor have grooves 33 formed in it, the grooves 33 being spiral and substantially co-extensive with the ducts 32 formed within the rotor, the 100

105

110

115

120

grooves terminating some distance from the recess 27 formed in the rotor. Throughout the major portion of the housing and the rotor, a running fit is provided between the 5 side walls of these two elements as shown in the lower portion of Fig. 5, and at one place in the housing, preferably adjacent the discharge pipe 34, the inner walls of the housing are recessed, as shown at 35 and 36 10 in the upper portion of Fig. 5. The ducts 32 and grooves 33 are adapted to empty into the discharge channel 37. A nozzle 38 reduces the width of the discharge channel at a distance from the rotor and is adapted to 15 direct the flow thru a reduced opening 39 in the nozzle into a gradually enlarging bore 40 formed in the discharge pipe 34. The nozzle 38 extends into a chamber 41 formed within the couplings 42. The pipe 43 communicates with the chamber 41. The fluid discharged by way of the pipe 34 is directed to a tank 44. A three way coupling 49 interposed in the pipe 48 permits communication, thru an inverted U shaped pipe connection 50, between the pipe 48 and pipes 29 20 and 30. The end of the pipe 34 disposed within the tank 44, carries and communicates with the bore 45 of the coupling 46. The end 47 of the coupling 46 is adapted to 25 discharge into the tank 44. A cage valve 51 is slidably contained within the bore 45, and comprises a forward diaphragm 52 and a perforated rear diaphragm 53 which diaphragms are retained in spaced relation by 30 spacing arms 54. The rear diaphragm 53 has formed in it a slot 55 whereby communication between the intermediate chamber 56, formed between the diaphragms, may be established with a rear chamber 57 located 35 within the coupling between the abutment 58, forming a closure for one end of the bore 45, and the rear diaphragm 53. The diaphragm 53 carries abutment lugs 59 adapted to engage the abutment 58 thereby precluding 40 elimination of the chamber 57. A by-pass 60 is formed in the coupling 46, and is adapted to establish communication between the bore 45 in one end of the coupling and the bore 61 in the other end of the coupling, 45 the abutment 58 forming a wall or diaphragm separating the inner ends of the bores 45 and 61. Normally the by-pass 61 communicates with the intermediate chamber 56 as shown in Fig. 9, and the pipe 34 50 is adapted to discharge into the tank 44 thru the open or forward end of the bore 45. When the cage valve is reciprocated longitudinally of itself, the diaphragm 52 may assume a position intermediate the mouth of the pipe 34 and the mouth or open end 47 of the bore, wherefore communication between the pipe 34 and the by-pass 60 may be established. A pipe 62 communicates 55 with the second bore 61 in the coupling, and is adapted to direct fluid from the bore 61 to a boiler 63 forming part of a radiating system. The boiler 63 is in communication with radiators 64 of the heating system, as is common in the art. The cage valve is controlled by a float 65 contained within the 60 tank 44. The float 65 is mounted at one end of a float rod 66, the other end of which float rod is mounted on one arm 67 of a bell crank lever 68 pivotally mounted on suitable brackets 69 mounted on the tank 44. The other arm 70 of the bell crank lever is connected with a valve stem 71 extending from the diaphragm 52 of the cage valve, by means of a link 72, the ends of which link are pivotally mounted on the valve stem 71 65 and the lever arm 70. As the float 65 is raised in the tank 44, the cage valve is actuated whereby to place the pipe 34 in communication with the by-pass 60, thereby avoiding overflow of the tank 44 and directing the fluid to the boiler 63. A standard 73 carried by the coupling 46 extends downwardly into the tank and carries at its lower end a block 74 having a horizontal bore 75 there-thru, in which bore 75 is revolvably 70 contained a tube shaft 76 having mounted on its one end a float stem 77 carrying a float 78. Suitable collars 79 and 80 are mounted on the tube shaft to preclude displacement 75 of the tube shaft. A pipe 81, extending between the coupling 46 and the block 74 has its opposite ends in communication with the chamber 57 in the coupling and the bore 75 in the block 74. The revolute tube 76 has 80 formed in it a slot 82 bearing such a relation to the pipe 81 that the rotatory motion of the tube serves to place the slot 82 into registration with and removes the slot from registration with the bore of the pipe 81. The slot 82 extends thru the wall of the tube shaft, whereby the bore of the pipe may be placed in communication with the bore of the tube shaft. The bore in the tube shaft is open at the ends of the tube shaft. As the float 78 is raised and lowered the chamber 57 85 in the coupling 46 is alternately placed in and out of registration with the bore in the tube 76. When the chamber 76 in the coupling is in communication with the bore in the tube 76 the cage valve 71 may be freely reciprocated in the coupling bore. The tube 76 is so disposed in relation to the normal supply of water in the tank 44 that the tube is at all times submerged. 90

As the first mentioned float 65 is raised, it engages the arm 82 of the pivotally mounted bell crank lever 83. The bell crank lever may be mounted in any suitable manner, for example, on a bracket 84 mounted on the coupling 46. The second arm 85 of the bell crank lever 83 is pivotally connected with one end of a rod 86, the other end of which rod 86 is pivotally mounted on a crank arm 87 of an oscillating valve 88. The oscillating valve 88 serves as a control for a pres- 95

100

105

110

115

120

125

130

sure valve 89. The pressure valve 89 controls the operation of the motor 13. The oscillating valve 88 comprises a base 90 having bores 91 and 92 which communicate with pipes 93 and 94. The pipe 93 communicates with the pipe 43 intermediate a check valve 95 disposed in the pipe 43, and the radiators 64 of the heating system. A suitable vacuum gauge 96 may be interposed in the pipe 93. The pipe 94 communicates with a bellows or other suitable actuating means in the pressure gauge 89, whereby pressure within the pipe 94 will control the operation of the valve 89 whereby to open and close an electrical circuit 105 embracing suitable movable contacts forming part of the pressure gauge 89. The circuit 105 embraces the motor 13 in a suitable source of electrical energy such as the battery 97. Any suitable device adapted to function as does the device 89 may be employed. The base 90 of the valve 88 carries a suitable housing 98 within which is movably contained a valve member 99 having an arcuate groove 100 in its under-face, which groove is adapted to be placed in registration with slots 101 and 102 formed in the base 90 and communicating with the bores 91 and 92. The base 90 has formed in it a perforation 103 which may be placed in registration with slots 101 and 102 formed in the base 90 and communicating with the bores 91 and 92. The base 90 has formed in it a perforation 103 which may be placed in registration with the groove 100 in the valve member 99. The valve member 99 is provided with a suitable head 104 upon which is mounted the crank arm 87. Normally the groove 100 assumes a position such that the slots 101 and 102 communicate with one another thru the groove 100, as shown in dotted lines A, in Fig. 12, wherefore the device 89 is normally subjected to any pressure within the heating system. When the valve member 99 is actuated to such extent in a clock-wise direction, see Fig. 12, that the groove 100 assumes the position shown by dotted lines B, the bore 92 is placed in communication with the perforation 103, and the slot 101 is sealed. The device 89, with which the bore 92 communicates, is so adjusted, that when the pressure operative upon the parts of said device reaches a determinable point, the circuit 105 is completed. The circuit 105 will be completed under two conditions. These two conditions are, first, when the pressure within the heating system rises to the determinable point, and secondly, when the pipe 94 is placed in communication with the atmosphere. As soon as the circuit embracing the motor 13 is closed, the motor becomes operative and rotates the rotor 9 contained within the housing 14.

The operation of my device is as follows: A suitable quantity of fluid, such as water

106, is placed in the system comprising a tank 44 and boiler 63, and the motor 13 is revolvably actuated, the motion of the motor being transmitted to the rotor 9 by means of the shaft 8. The rotor is revolved at a high rate of speed, and the water supplied thru the pipe 30 and duct 28 is thrown outwardly by the rotor and passes off thru the discharge pipe 34, and returns to the tank 44. The water which is supplied to the rotor enters the ducts 270 and 28 and the tendency to the creation of a vacuum in the pipe 29 and duct 270, serves, at all times, to provide an adequate supply of water for the efficient cooperation of the fluid and the rotor. When the fluid is thrown outwardly by the rotor, it passes thru the nozzle 38, and whereas the nozzle 38 has a reduced end 39, the water passes thru the chamber 42 into the bore 40 in the pipe 34 at a tremendous velocity, the water carrying with it such air or other fluid which may be in the chamber 41. The grooves formed on the rotor co-operate with the spiral ducts in the rotor in effecting the desired velocity of the water as it is discharged. The water is supplied to the grooves by way of the recesses 36 formed in the walls of the housing, and which recesses are supplied with water from the ducts as they communicate with said recesses. The grooves bear such a relation to the discharge duct that the grooves may discharge into said duct. If the supply of fluid in the tank 44 becomes too great, the valve 45 is closed off by the float 65 and the fluid is then discharged into the system by way of the pipe 62. Condensation in the radiators passes thru the check valve and flows into tank 44. When the water in the tank reaches a determinable height, the motor is actuated as previously explained.

What I claim is:

1. In a device of the class described the combination of a housing having a chamber within it, a rotor revolvably contained within the chamber having a recessed center and spiral ducts extending from the recess to the periphery thereof, the housing having a discharge channel into which the ducts in the rotor may discharge, a valve block extending into the housing having its one end disposed within the recess in the rotor, and having a pair of ducts, formed in it, the ducts being disposed in a substantially vertical relation and being adapted to be placed in alternate communication with the ducts in the rotor, a fluid supply tank, a supply pipe adapted to establish communication between the supply tank and the lower duct in the valve block, a connection extending above the valve block establishing communication between the supply pipe and the upper duct in the valve block, a discharge nozzle mounted on the housing communicat-

- ing with the discharge channel and having a reduced discharge end, a coupling having a chamber formed within which chamber the discharge end of the nozzle is disposed, and 5 a pipe extending into the chamber in the coupling into which the discharge nozzle is adapted to direct the flow of fluid which passes thru said nozzle, the pipe being spaced from the nozzle and having a bore 10 which is gradually enlarged as it recedes from the nozzle, and means to establish communication between the chamber in the coupling, and a container within which the pressure is to be reduced.
- 15 2. In a device of the class described, the combination of a housing having a chamber formed within it, a rotor revolvably mounted within the chamber having a central recess, spiral ducts extending from the recess to the 20 periphery thereof, and spiral grooves upon its opposite sides extending in the same direction as do the ducts and terminating upon the periphery of the rotor, the housing having recessed inner walls whereby communication 25 between the grooves may be effected and whereby fluid discharged from the ducts may enter said grooves, a valve block extending into the recess in the rotor having an upper and a lower duct with which the 30 ducts in the rotor alternately communicate, a supply pipe whereby a fluid may be supplied to the ducts in the valve block, means to revolve the rotor, and a discharge pipe whereby fluid may leave the chamber within the 35 housing.
3. In a device of the class described, the combination of a housing having a chamber formed within it, a rotor revolvably mounted within the chamber having a central recess, 40 spiral ducts extending from the recess to the periphery thereof, and spiral grooves upon its opposite sides extending in the same direction as do the ducts and terminating upon the periphery of the rotor, the 45 housing having recessed inner walls whereby communication between the grooves may be effected and whereby fluid discharged from the ducts may enter said grooves, a valve block extending into the recess in the rotor 50 having an upper and a lower duct with which the ducts in the rotor alternately communicate, a supply pipe whereby a fluid may be supplied to the ducts in the valve block, means to revolve the rotor, and a 55 discharge nozzle communicating with the chamber within the housing having a reduced discharge end, a coupling having a chamber within which the discharge end of the nozzle is disposed, a pipe extending into the chamber in the coupling and having a mouth into which the fluid discharged by the nozzle is directed.
- 60 4. In a device of the class described, the combination of a housing having a chamber formed within it, a rotor revolvably mounted 65 within the chamber having a central recess, spiral ducts extending from the recess to the periphery thereof, and spiral grooves upon its opposite sides extending in the same direction as do the ducts and terminating upon the periphery of the rotor, the housing having recessed inner walls whereby communication between the grooves may be effected and whereby fluid discharged from the ducts may enter said grooves, a valve block extending into the recess in the rotor having an upper and a lower duct with which the ducts in the rotor alternately communicate, a supply pipe whereby a
- within the chamber having a central recess, spiral ducts extending from the recess to the periphery thereof, and spiral grooves upon its opposite sides extending in the same direction as do the ducts and terminating 70 upon the periphery of the rotor, the housing having recessed inner walls whereby communication between the grooves may be effected and whereby fluid discharged from the ducts may enter said grooves, a valve 75 block extending into the recess in the rotor having an upper and a lower duct with which the ducts in the rotor alternately communicate, a discharge nozzle communicating with the chamber within the housing 80 having a reduced discharge end, a coupling having a chamber within which the discharge end of the nozzle is disposed, and a pipe extending into the chamber in the coupling and having a mouth into which the fluid discharged by the nozzle is directed, the pipe having a gradually enlarging bore receding from the mouth thereof.
5. In a device of the class described, the combination of a housing having a chamber 90 formed within it, a rotor revolvably mounted within the chamber having a central recess, spiral ducts extending from the recess to the periphery thereof, and spiral grooves upon its opposite sides extending in the same 95 direction as do the ducts and terminating upon the periphery of the rotor, the housing having recessed inner walls whereby communication between the grooves may be effected and whereby fluid discharged from the 100 ducts may enter said grooves, a valve block extending into the recess in the rotor having an upper and a lower duct with which the ducts in the rotor alternately communicate, means to revolve the rotor, a discharge nozzle communicating with the chamber within the housing having a reduced discharge end, a coupling having a chamber within which the discharge end of the nozzle is disposed, a pipe extending into the chamber in the 105 coupling and having a mouth into which the fluid discharged by the nozzle is directed.
6. In a device of the class described, the combination of a housing having a chamber 110 formed within it, a rotor revolvably mounted within the chamber having a central recess, spiral ducts extending from the recess to the periphery thereof, and spiral grooves upon its opposite sides extending in the same 115 direction as do the ducts and terminating upon the periphery of the rotor, the housing having recessed inner walls whereby communication between the grooves may be effected and whereby fluid discharged from the ducts may enter said grooves, a valve block extending into the recess in the rotor having an upper and a lower duct with which the ducts in the rotor alternately communicate, a supply pipe whereby a

fluid may be supplied to the ducts in the valve block, means to revolve the rotor, a discharge pipe whereby fluid may leave the chamber within the housing, 5 and means to establish communication between the discharge pipe and a container, the pressure within which container is to be reduced.

7. In a device of the class described, the 10 combination of a housing having a chamber formed within it, a rotor revolvably mounted within the chamber having a central recess, spiral ducts extending from the recess to the periphery thereof, and spiral grooves 15 upon its opposite sides extending in the same direction as do the ducts and terminating upon the periphery of the rotor, the housing having recessed inner walls whereby communication between the grooves may be effected 20 and whereby fluid discharged from the ducts may enter said grooves, a valve block extending into the recess in the rotor having an upper and a lower duct with which the ducts in the rotor alternately communicate, a discharge nozzle communicating 25 with the chamber within the housing having a reduced discharge end, a coupling having a chamber within which the discharge end of the nozzle is disposed, a pipe extending 30 into the chamber in the coupling and having a mouth into which the fluid discharged by the nozzle is directed, means whereby the chamber within the coupling may be placed in communication with a container, the pressure 35 within which is to be reduced, means to revolve the rotor, and means to supply fluid to the lower duct in the valve block communicating also with the upper duct in the valve block.

40 8. In a system of the class described the combination of a boiler, radiators, pipes connecting the boiler and the radiators, a rotor pump adapted to operate upon a fluid and to throw the fluid outwardly from its center, a coupling associated with the rotor having a chamber thru which the fluid passes from the rotor, a fluid supply tank, a pipe connecting the coupling and the fluid supply tank, means to divert fluid from the last mentioned pipe to the boiler, 45 a valve block adapted to direct fluid to the rotor adjacent the center thereof having an upper and a lower duct, a pipe communicating with the supply tank and the lower duct in the valve block, a connection 50 between the upper duct in the valve block and the last mentioned pipe, the connection extending above the valve block, a pipe communicating with the radiators and the coupling, means to revolvably actuate the rotor, a pressure 55 valve controlling the rotor actuating means adapted to be placed in communication with the last mentioned pipe, a valve interposed between the pressure valve and the last mentioned pipe adapted to place the pressure valve in communication with the last mentioned pipe and with the atmosphere, means within the supply tank controllable by the fluid contents of the tank 60 adapted to actuate the valve interposed between the pressure valve and the last mentioned pipe, and to control the fluid diverting means, and means controllable by the fluid contents of the supply tank for locking the fluid diverting means.

adapted to place the pressure valve in communication with the last mentioned pipe and with the atmosphere, and means within the supply tank controllable by the fluid contents of the tank adapted to actuate the 70 valve interposed between the pressure valve and the last mentioned pipe, and to control the fluid diverting means.

9. In a system of the class described the combination of a boiler, radiators, pipes connecting the boiler and the radiators, a rotor pump adapted to operate upon a fluid and to throw the fluid outwardly from its center, a coupling associated with the rotor having a chamber thru which the fluid passes from the rotor, a fluid supply tank, a pipe connecting the coupling and the fluid supply tank, means to divert fluid from the last mentioned pipe to the boiler, a valve block adapted to direct fluid to the rotor adjacent the center thereof having an upper and a lower duct, a pipe communicating with the supply tank and the lower duct in the valve block, a connection between the upper duct in the valve block and the last mentioned pipe, the connection extending above the valve block, a pipe communicating with the radiators and the coupling, means to revolvably actuate the rotor, a pressure 80 valve controlling the rotor actuating means adapted to be placed in communication with the last mentioned pipe, a valve interposed between the pressure valve and the last mentioned pipe adapted to place the pressure valve in communication with the last mentioned pipe and with the atmosphere, means within the supply tank controllable by the fluid contents of the tank adapted to actuate the valve interposed between the pressure valve and the last mentioned pipe, and to control the fluid diverting means, and means controllable by the fluid contents of the supply tank for locking the fluid diverting means.

10. A fluid diverting device of the class described comprising a coupling having a bore at its opposite ends, a diaphragm sealing the ends of the bores from communication, the coupling having a by-pass whereby communication between the bores may be established, a connection whereby fluid may be directed to one of said bores, a cage valve reciprocally contained within the one bore controlling communication between the connection and the by-pass, a supply tank into which the one bore is adapted to discharge, and into which fluids passing thru the connection are directed by the coupling when the cage valve closes off communication between the connection and the by-pass, and means within the supply tank controllable by the fluid contents of the supply tank adapted to reciprocate the cage valve.

11. In a system of the class described the combination of a boiler, radiators, pipes con-

necting the boiler and the radiators, a rotor pump adapted to operate upon a fluid and to throw the fluid outwardly from its center, a coupling associated with the rotor having a chamber thru which the fluid passes from the rotor, a fluid supply tank, a pipe connecting the coupling and the fluid supply tank, means to divert fluid from the last mentioned pipe to the boiler, a valve block 5 adapted to direct fluid to the rotor adjacent the center thereof having an upper and a lower duct, a pipe communicating with the supply tank and the lower duct in the valve block, a connection between the upper duct in the valve block and the last mentioned pipe, the connection extending above the valve block, a pipe communicating with the radiators and the coupling, means to revolvably actuate the rotor, a pressure valve controlling the rotor actuating means adapted 10 to be placed in communication with the last 15 20

mentioned pipe, a valve interposed between the pressure valve and the last mentioned pipe adapted to place the pressure valve in communication with the last mentioned pipe 25 and with the atmosphere, means within the supply tank controllable by the fluid contents of the tank adapted to actuate the valve interposed between the pressure valve and the last mentioned pipe, and to control 30 the fluid diverting means, means within the supply tank controllable by the fluid contents of the supply tank adapted to reciprocate the cage valve, and a second means controllable by the fluid contents of the supply tank for locking the cage valve 35 against reciprocation.

In testimony whereof, I have hereunto subscribed my name this 21st day of June, 1922.

VICTOR ROSENHAGEN.
